UNITED STATES PATENT OFFICE.

ALBERT N. WOODRUFF, OF NEW YORK, N. Y.

COPY-HOLDER.

1,383,897.

Specification of Letters Patent. Patented July 5, 1921.

Application filed April 9, 1920. Serial No. 372,487.

To all whom it may concern:

Be it known that I, ALBERT N. WOODRUFF, a citizen of the United States, and a resident of the city of New York, borough of Manhattan, in the county and State of New York, have invented a new and Improved Copy-Holder, of which the following is a full, clear, and exact description.

The present invention relates to new and useful improvements in copy holders, and it pertains more particularly to a line-spacing mechanism therefor.

It is the primary object of the present invention to provide a copy holder in which a line-spacing mechanism is moved intermittently from the top to the bottom of the writing bed in such a manner that the line being copied by the operator will at all times be positioned above the line indicator.

It is a further object of the invention to so construct a line-spacing mechanism that it is movable in one direction only by the intermittently operated means.

It is a further object of the invention to provide a line spacer which is capable of movement to release the intermittently operated mechanism in order that the same may be moved freely from the bottom or lower end to the upper end of the writing bed to re-position it with respect to the manuscript copy when the operator has finished each page.

Referring to the drawings—

Figure 1 is a side elevation of a copy holder constructed in accordance with the present invention;

Fig. 2 is a front elevation thereof;

Fig. 3 is a rear elevation partly in section of the invention;

Fig. 4 is a transverse sectional view taken on the line 4—4 of Fig. 3;

Fig. 5 is an end view of the upper end of the writing bed;

Fig. 6 is a detail sectional view of the carriage and a portion of its operating mechanism;

Fig. 7 is a detail sectional view showing the mechanism for preventing movement of the line spacer in one direction.

Referring more particularly to the drawings, the reference character 10 designates the writing bed of the copy holder, and said bed is supported at one end by means of a suitable bracket 11, and at its opposite end by means of a bracket 12. The bracket 11 is rigidly secured to a flange 13, which in turn is rigidly carried by the lower end

of the writing bed 10. The bracket 12, however, is hingedly secured in ears 14 secured to the under side of the bed 10, as best shown in Fig. 3, and said bracket 12 is adapted to fold against the rear side of the bed 10 when the device is not in use. Each of these brackets 11 and 12 is provided with a friction producing covering in the form of a rubber sleeve 15 passed over that portion which engages the support by which the bracket is carried.

The writing bed 10 is provided on its upper end with a flange 20, which depends therefrom, and extending beyond said flange and overlying the same is a channel 21 in which is adapted to engage a paper or book clamping element 22. Thus the clamping element 22 is mounted in a rigid bracket 23 carried by the rear face of the writing bed 10, and the clamping portion thereof is adapted to be maintained in position in the channel 21 by means of a spring 24, one end of which engages the bracket as at 25, the other end 26 engaging the right-angular arm 27 of the paper clamp 22.

Rigidly secured at its ends to the flanges 13 and 20 and arranged near one side of the writing bed 10, is a rigid rod 30. The reference character 31 designates a carriage, and said carriage has one of its ends turned about the rod 30 as indicated at 32, it being understood that the end 32 freely engages the rod 30 in order to permit of a sliding movement of the carriage 31. The opposite end of the carriage 31 is provided with a substantially right-angular extension 33, and the body portion of the carriage 31 and the right-angular extension 33 are each provided with right-angular ears 34, each of which is perforated as indicated by the reference character 35. A rod 36 is reciprocatively mounted in openings in the flanges 13 and 20. Rigidly secured to the upper end of the rod 36, as at 37, is a spring 38, and said spring passes around a pintle or rigid pin 39 and has its looped central portion extended inwardly through a slot 40 in the flange 20 and engages a pin 41 to prevent accidental displacement of the spring.

The lower end of the rod 36 is screw-threaded as at 42 and engaged thereon is a nut 43, and 44 designates a button or thumb-engaging member by means of which the rod 36 is reciprocated in the flanges 13 and 20. The nut 43 serves the means by which the throw of the rod 36 is regulated,

it being obvious that if the nut 43 is moved over the threaded portion 42 to a point nearer to the flange 13 than that shown in Fig. 3, the throw of the rod 36 will be materially shortened. Therefore this rod can move only until the nut 43 engages the flange 13. From this construction it will be seen that the rigid rod 30 and the reciprocating rod 36 form the means by which the carriage 31 is mounted for reciprocating movement on the rear side of the bed 10.

Pivotedly mounted on the carriage 31, as in perforated ears 50, is a line-spacing element 51, and said line-spacing element extends around the side of the writing bed 10 to the front or top portion thereof, as indicated at 52. By means of a spring 53, one end of which is secured as at 54 to the carriage 31 and the other end embracing the line indicator as at 55, the portion 52 of the line indicator is maintained at all times in engagement with the paper or book carried by the writing bed 10.

Suitably mounted by means of a bolt or the like 60, on the under side of the carriage 31, is a lever 61, and said lever 61 is provided with a notch or cut-out portion 62 adapted to engage the reciprocating rod 36. This lever 61 is provided with an angularly disposed thumb-engaging portion 63, by means of which it may be rocked about its pivot to a point where it disengages the rod 36 to permit of a free movement of the carriage upwardly of the bed 10. This pivoted lever 61 is maintained normally in engagement with the rod 36 at one end 64 of a spring 65 mounted on a rigid bolt 66 secured to the carriage.

On the under side of the carriage is a dog 68 or similar pivoted member 68, pivoted as at 67, which dog is adapted to engage the writing bed 10 as indicated by the reference character 69. As indicated at 70, a portion of the bed is corrugated or roughened in order that the dog or pawl 68 may obtain a grip thereon. This dog or pawl 68 is normally maintained in engagement with the bed by the other end 71 of the spring 65, as best seen in Fig. 4.

The device operates in the following manner:

Assuming that the device is positioned as in Fig. 1 and it is desired to move the line indicator 52 to the left or downwardly of the bed 10,—the operator pushes upward the button 44 and reciprocates the rod 36 upwardly of the bed 10. As this rod is reciprocated the pivoted lever 61 is rocked sufficiently to permit of a free movement of said rod, the dog or pawl 68 due to its engagement with the under side of the bed 10 preventing a movement of the carriage. When, however, pressure on the operating button 44 is released under the influence of the spring 38, the rod will be returned to its normal po-

sition, and as it moves to its normal position the pivoted lever 61 bites upon the rod 36, and through this biting engagement moves the carriage with the rod on its return movement.

From the foregoing it will be seen that the present invention provides a simple mechanism by which the line indicator of a copy holder may be moved step by step, the distance of travel of which may be varied at the will of the operator.

I claim:

1. In a copy holder, a writing bed, means for supporting the writing bed, a rod rigidly carried by the writing bed, and a second rod reciprocatively carried by the writing bed, a carriage mounted upon the rigid rod and the reciprocating rod, a pivoted pawl mounted on the carriage and adapted to engage the writing bed to prevent movement of the carriage in one direction, a line indicator carried by the carriage and movable with respect thereto, and means carried by the carriage and adapted for operation upon movement of the line indicator to release the engagement of the pawl with the writing bed to permit movement of the carriage longitudinally of the writing bed in either direction.

2. A copy holder comprising a writing bed having a roughened portion on its rear face, a carriage movable longitudinally of the rear face of said writing bed, a pivoted pawl carried by the carriage and adapted for engagement with the roughened surface of the writing bed to prevent movement of the carriage in one direction, a swinging line indicator mounted on the carriage and projecting to the front face of the writing bed, and means adapted for operation by the swinging movement of the line indicator for disengaging the pawl from the roughened surface of the writing bed to permit movement of the carriage longitudinally of the writing bed in either direction.

3. In a copy holder, a writing bed, a carriage mounted upon the writing bed, means reciprocatively mounted with respect to the writing bed for moving the carriage therewith, a resiliently mounted pivoted pawl carried by the carriage and adapted for engagement with the writing bed to prevent movement of the carriage in one direction upon operation of the reciprocating carriage-moving means, a line indicator carried by the carriage and adapted for pivotal movement with respect thereto, and means positioned in the path of the line indicator whereby when said line indicator is rocked about its pivotal point, the pawl will be released from engagement with the writing bed to permit of free reciprocal movement of the carriage in either direction.
